ELECTRIC SWITCHES AND PARTS THEREFOR

Robert O. Perrine, Wauwatosa, Wis., assignor to Cutler-Hammer, Inc., Milwaukee, Wis., a corporation of Delaware

Application July 20, 1953, Serial No. 369,086

3 Claims. (Cl. 200—67)

This invention relates to electric switches and parts therefor, and it relates more particularly to manually operable snap-acting mechanisms and to electric switches including snap-acting mechanisms automatically responsive to a condition to operate the switch and manually operable to alter such automatic operation.

Most switches which are automatically operable in response to a condition, such, for example, as float, pressure and refrigeration switches, are required to include snap-acting mechanism for very rapid actuation of the switch contacts. In certain applications of such switches it is also required or desirable to incorporate in the switch manually operable means to alter the operation or to render ineffective said snap-acting mechanism with respect to a given normally automatic operation of the switch.

A primary object of the invention is to provide an improved snap-acting mechanism which, while not limited thereto, is particularly suited for manual operation and which is inexpensive to manufacture and assemble and is readily adaptable for use in a variety of switches.

An object is to provide a switch having snap-acting mechanism for actuating the switch contacts in response to a condition and further having manually operable snap-acting mechanism to render the former snap-acting mechanism ineffective. Such manually operable mechanism provides a means to selectively set the device controlled by the switch or to fix the switch circuit in a given condition and further provides that the manual commutation of the switch contacts will be accomplished with the required rapidity.

Another object is to provide a switch of the character described in which the manually operable snap-acting mechanism is independent of the condition-responsive snap-acting mechanism. This feature of the switch prevents the operating differential of the switch and the normal operation of the condition-responsive snap-acting mechanism from being affected by the manual mechanism or by operation of the latter.

Other objects and advantages of the invention will hereinafter appear.

The accompanying drawings illustrate an embodiment of the invention which will now be described. It is to be understood that various modifications may be made in the structural details thereof without departing from the spirit of the invention or the scope of the appended claims.

In the drawings, Figure 1 is a partly diagrammatic and partly mechanical fragmentary side view of a switch embodying the invention;

Fig. 2 is a similar fragmentary front view of the switch shown in Fig. 1;

Fig. 3 is a top plan view of a preferred form of the manually operable snap-acting mechanism employed; and

Fig. 4 is a side view of a preferred form of the bowed spring employed in the manually operable snap-acting mechanism illustrated in Fig. 3, shown in relaxed condition.

Referring to Fig. 1 of the drawing, the numeral 10 gen-

erally designates snap-acting mechanism shown diagrammatically. Mechanism 10 may be of the type disclosed and claimed in Robbins Patent No. 2,375,387, granted May 8, 1945, to the assignee of the present application.

5 It comprises, as shown, a snap-acting lever 12 pivoted at a point 14, and a second lever 16 pivoted at a point 18 for rotational movement between spaced stops 20 and 22, and continually biased for rotation toward stop 22 by over-center spring 24 held under tension between a point 26 on snap-acting lever 12 and a point 28 on the second lever 16. The mechanism 10 further comprises a switch operating member 30 having a portion 30^a engaging the upper surface of the second lever 16. Member 30 is movable to rotate said lever 16 toward stop 20 or to permit the lever 16 to be rotated toward stop 22 in accordance with a condition represented by a force acting in opposition to a main spring 32. The spring 32 is interposed between member 30 and a range adjustment mechanism 34.

20 The switch contact mechanism is illustrated diagrammatically. A set of normally closed contacts comprising contacts 40, 40, and a bridging contactor 42, are shown.

A push-bar 44, preferably composed of insulating material, is provided to transmit the snap movement of snap-acting lever 12 to the bridging contactor 42. Means, such as a spring 46 acting on the bridging contacts, are provided to urge the push-bar 44 downwardly unless such movement is prevented by snap-acting lever 12 or by the manually operable snap-acting mechanism generally designated 48. Mechanism 48 is hereinafter more fully de-

30 scribed. The push-bar 44 is provided with a lateral extension 50 at its upper end and a lateral extension 52 at its lower end. A differential adjustment screw 54 having a kerfed upper end 56, a shank 58 which is threaded at 58^a, and which terminates at its lower end in a flanged portion 60 and a head portion 62, extends through an opening in the lower extension 52 of the push-bar 44. The portion 58^a of screw 54 is adapted for adjustable engagement with a correspondingly internally threaded opening in portion 40 of the switch frame.

40 The over-center spring 24 urges the second lever 16 upward, against the portion 30^a of member 30. Thus the lever 16 is positioned in accordance with the relative magnitudes of the external force acting upwardly, and the

45 force of the main spring 32 acting downwardly, on member 30. When, as shown, lever 16 is positioned so that the axis of over-center spring 24 is below the pivot 14 of the snap-acting lever 12, the latter lever is biased downwardly by over-center spring 24 so that its end 12^a engages 50 the upper surface of flange 60. Unless restrained, as shown, by snap-acting mechanism 48, the push-bar 44 is moved downwardly by spring means 46 into engagement with lever 12. In that position of the push-bar, contacts 40, 40 are engaged by bridging contactor 42.

55 If member 30 is moved upwardly permitting upward movement of lever 16 to carry the axis of over-center spring 24 above pivot 14, lever 12 will snap upwardly. End 12^a of lever 12 will lift the push-bar 44 to effect electrical disconnection of contacts 40, 40. The operating differential of the switch is determined by the arc through which point 26 on lever 12 is permitted to move and may therefore be adjusted by raising or lowering flange 60 by turning the differential screw 54.

60 The push-bar 44 may be selectively released for movement by lever 12 and spring means 46, as aforescribed, or may be lifted to its upper position as shown by snap-acting mechanism 48 so that snap-acting mechanism 10 has no effect thereupon.

65 Referring to Figs. 2 and 3, mechanism 48 includes a generally U-shaped spring 70 of suitable resilient metal and an operating lever 72 which are pivotally interconnected. The spring 70 and lever 72 are pivotally con-

nected to walls 74 and 76, respectively, of an inner switch frame and are trapped between said walls 74 and 76 so that spring 70 is held under compression. The extreme end 78 of one arm of spring 70 is of reduced width to form a pair of shoulders 80, 80. End 78 extends laterally into and opening 82 formed in wall 74 so that shoulders 80, 80 bear against the wall 74 to form a pivot for pivotal movement of spring 70 with respect to said wall 74. The other arm of spring 70 is provided with an opening 84 (Fig. 3) adapted to accommodate the reduced end portion 86 of operating lever 72.

Lever 72 is preferably formed from a strip of suitable resilient metal. Its reduced end portion 86 is adapted to provide a pair of shoulders 88, 88 which bear against spring 70 adjacent to opening 84 in the latter to form a pivot for relative pivotal movement between spring 70 and lever 72. The other end portion 90 of lever 72 is of reduced width to form a pair of shoulders 92, 92 at a point intermediate the length of the lever. Portion 90 extends through an opening 94 formed in wall 76 and shoulders 92, 92 bear against said wall adjacent to opening 94 to form a pivot for pivotal movement of lever 72 about the wall 76. The extreme outer end or handle portion 96 of lever 72 may be further reduced in width, as shown, to extend through an opening 98 formed in an outer frame or cover 100 of the switch. End 78 of spring 70, and portion 90 and handle 96 of lever 72 are preferably provided with integral offset portions or beads 102 and 104, respectively, to lend strength and rigidity thereto.

Mechanism 48 is disposed between walls 74 and 76 in such manner that at least a portion of lever 72 lies between flange 60 of differential screw 54 and the lateral extension 52 of push-rod 44. When handle 96 of lever 72 is depressed, the pivotal connection between lever 72 and spring 70 lies a short distance above a line connecting the pivotal connection of spring 70 with wall 74 with the pivotal connection between lever 72 and wall 76. Thus spring 70, which is under compression, urges lever 72 upwardly to lift push-bar 44 to its upper extreme position, as illustrated, and motion of snap-acting lever 12 is ineffective to change the position of the push-bar 44 or to actuate the switch contacts.

When handle 96 is lifted (see Fig. 2), the pivotal connection between lever 72 and spring 70 is carried below the line connecting their respective pivot shoulders 92 and 80 and lever 72 is snapped downwardly until it abuts flange 60. Thus the push-bar 44 is released for downward movement by snap-acting lever 12 and means 46.

If, while snap-acting lever 12 is disposed in the downward position, shown mechanism 48 is operated by movement of the handle 96 in either direction, the contacts 40, 40 will be opened or closed with a snap movement just as would be provided by mechanism 10. The operation afforded by mechanism 48 is provided without the necessity of modifying, connecting with, or otherwise complicating the primary control mechanism 10 and without complicating the operating differential adjustment mechanism. Moreover, mechanism 48 may readily be reversed so that the handle 96 extends from the opposite side of the switch. If preferred a handle portion (corresponding with portion 96) might extend from the spring 70 instead of from the lever 72.

The sizes of lever 72 and of spring 70, the latter being illustrated in relaxed condition in Fig. 4, are chosen so that when assembled in trapped relation between walls 74

and 76 and with lever 72 disposed between the push-bar 44 and flange 60, the spring 70 is continuously held under compression.

Mechanism 48 need comprise only two members in addition to the otherwise required frame walls 74 and 76 or their equivalent; no other fastening or auxiliary devices being required. Thus an easily assembled, inexpensive and dependable mechanism is provided.

I claim:

1. For combination with a switch, a switch operator movable to a switch actuating position, automatic snap-acting mechanism including a snap-acting lever engageable with said switch operator and responsive to a condition to move said switch operator to a switch actuating position, spaced frame members, a second snap-acting mechanism comprising an operating lever and a compression spring hingedly interconnected with said operating lever and trapped therewith between said spaced frame members, said operating lever and said spring each being hingedly connected to a respectively associated one of said spaced frame members and said operating lever being engageable with said switch operator, and directly manually operable handle to effect snap operation of said second snap-acting mechanism to urge said switch operator to said switch actuating position.
2. The combination defined in claim 1, including a member positioned for engagement by said snap-acting lever to limit movement of the latter when moved in a direction to release said switch operator from said switch actuating position to determine the operating differential of said switch, said last mentioned member being further positioned for engagement by said second snap-acting mechanism when snapped in a direction to release said switch operator from said switch actuating position to limit the motion thereof to less than that degree of movement required to release said spring from compression.
3. In combination, an electric switch including a switch operator member movable from a first to a second actuating position, means for biasing said member in said first position, snap-acting mechanism responsive to selected conditions to move said member to said second position and to release said member for movement by said bias means, spaced supports, and another snap-acting mechanism trapped between said supports and manually movable to engage said member and move the same to said second position and to release said member for movement by said bias means, said other snap-acting mechanism comprising a compression spring having an end thereof pivotally connected to one of said supports, and a lever having one end portion thereof pivotally connected to the other end of said compression spring and an intermediate portion pivotally connected to the other of said supports, said lever further having a second end portion for manually pivoting said lever for operation of said other snap-acting mechanism.
